UNITED STATES PATENT OFFICE

98,536

DESIGN FOR A HAND BRUSH

Elizabeth M. Maher, New York, N. Y., assignor to Pro-phy-lac-tic Brush Company, Northampton,
Mass., a corporation of Delaware

Application December 28, 1935, Serial No. 60,316

Term of patent 14 years

To all whom it may concern:

Be it known that I, Elizabeth M. Maher, a citizen of the United States of America, residing at New York, in the county of New York, State of New York, have invented a new, original, and ornamental Design for a Hand Brush, of which the following is a specification, reference being had to the accompanying drawing, forming a part thereof.

In the drawing:

Fig. 1 is a top plan view illustrating my new design for a hand brush, and

Fig. 2 is a side elevation.

I claim:

The ornamental design for a hand brush, substantially as shown.

ELIZABETH M. MAHER.
